UNITED STATES PATENT OFFICE.

WILLIAM Q. GLASS, OF LONG BEACH, CALIFORNIA.

MOP.

1,121,008.

Specification of Letters Patent.

Patented Dec. 15, 1914.

Application filed October 7, 1913. Serial No. 793,855.

To all whom it may concern:

Be it known that I, WILLIAM Q. GLASS, a citizen of the United States, residing at Long Beach, in the county of Los Angeles 5 and State of California, have invented a new and useful Mop, of which the following is a specification.

My invention relates to improvements in mops, and the object of my invention is to 10 provide a mop adapted to be used for dusting and cleaning under and around the legs of chairs, tables, radiators and the like and other places otherwise inaccessible to dust cloths, brooms, etc.

15 Other objects may appear in the accompanying detailed description.

I attain this object by means of mechanism illustrated in the accompanying drawings, in which—

20 Figure 1 is a side elevation of my mop. Fig. 2 is a perspective view of the mop frame or body showing the manner of securing the handle thereto. Fig. 3 is a sectional elevation typical of both sides of 25 the mop on the line x^4-x^4 , Fig. 1. Fig. 4 is a sectional elevation typical of both sides of 30 the mop on the line x^3-x^3 , Fig. 1.

The same reference numerals refer to like parts throughout the several views of the 35 drawings.

The mop frame consists of a single flat U-shaped bar 1 having the perforations 2 in each of its sides in which the handle 3 may be secured pivotally by means of the 40 resilient members 4 and 5 which are rigidly secured in the end of the handle 3 at one end and are bent outwardly at their other ends to engage the perforations 2. The 45 mop 8 may be of any suitable material but preferably of cotton strand as shown herein, the inner portions of the strands being woven together to form a flat surface 6 to which is sewed a double thickness of tape 7 and another thickness of this tape is sewed 50 to this double thickness at the top and bottom edges to form a slip adapted to be drawn over and to hold the mop on the frame 1. The handle 3 is pivoted near the 55 center of the frame 1 and that portion of the frame extending from the handle to the open ends is provided with and completely covered by two sections of the strand or 60 mop material, one being on the outside and one on the inside of the frame as shown in 65 Fig. 4, in this case the double thickness of tape on each section being sewed together 70

and the slip formed between them. The other portion of the frame has only a single section of the mop material on its outside, as shown in Fig. 3.

60 A slight resiliency is afforded in the sides of the frame 1, and as the open ends are covered on both sides of the frame the mop is thereby adapted to straddle a chair or table leg and simultaneously dust or clean 65 all of its sides, the resiliency of its sides serving to hold the mop in close contact with the leg. The mop is adapted to be pushed or drawn along the floor, walls or ceiling and the handle may be used in a 70 horizontal position as shown in dotted lines in Fig. 1 for cleaning under beds, dressers or other articles of furniture where a broom or other styles of mop may not be used.

75 The handle 3 may be removed from the frame 1 by compressing the members 4 and 5 and it may be inserted in the frame in a similar manner. A mop may be easily removed from the frame and a new one placed in position by removing the handle, 80 drawing the mop off toward the open end of the frame, placing the new one in position at the open end so that the slip between the tapes will slide over the ends of the frame 1 and drawing it toward the back 85 of the frame.

85 This mop may be used for ordinary dusting in a dry state, may be coated with kerosene or other oils, or may be used for mopping and cleaning with water, as in the 90 case of other styles of mops.

95 What I claim as my invention and desire Letters Patent for, is:

1. In a mop, the combination of a bifurcated frame; a handle resiliently and 95 pivotally secured thereto, near the center; a slip of fabric adapted to slip over and completely cover said frame; and a mop of suitable stranded material, woven together and suitably secured to said fabric; 100 said mop being adapted to be used with the handle in a horizontal position or at an angle to the floor, and being adapted to straddle and simultaneously engage and clean all sides of and around the legs of 105 chairs and the like, as described.

110 2. In a mop, the combination of a U-shaped frame, having a slight resiliency and having a perforation in each of the sides thereof, near the center and oppositely positioned; a double pronged, resilient handle adapted to pivotally seat in said perforations, and

to swing, when in use, toward or in the open end of said frame; a slip of two-ply tape, sewed together at the edges and adapted to slip over said frame; a mop of suitable stranded material, woven together, and suitably secured to said slip on both sides of said frame, for adapting said mop to

straddle and simultaneously engage and clean all sides of and around the legs of chairs and the like, as described.

WILLIAM Q. GLASS.
